UNITED STATES PATENT OFFICE.

ALEXANDRE VAUGEAN, ANTHONY DE LAVANDEYRA, AND WILLIAM GARTHWAITE, OF PARIS, FRANCE.

MICROPHONE.

1,230,956.

Specification of Letters Patent. Patented June 26, 1917.

Application filed October 15, 1915. Serial No. 56,107.

To all whom it may concern:

Be it known that we, ALEXANDRE VAUGEAN, subject of the King of Roumania, ANTHONY DE LAVANDEYRA, citizen of the Republic of Brazil, and WILLIAM GARTHWAITE, subject of the King of Great Britain, residing the first at 18 Rue Saint Senoch, Paris, France, the second at 9 Rue Léo Delibes, Paris, France, the third at 7 Rue Meyerbeer, Paris, France, have invented a new and useful Improvement in Microphones, which improvement is fully set forth in the following specification.

This invention relates to microphones for use in telephony. Reduced to its simplest expression, the theory of the microphone is contained in the three words "a variable resistance." Usually this variable resistance is obtained by variable intensity of pressure exerted by the action of the sound waves on the imperfect contacts of several carbon elements. The agglomerations of carbon possess in fact the property of having a conductivity which is variable according to the degree of pressure to which their points of contact are subjected.

If the fact is considered that the variable resistance of a microphone system must never attain such a high value as to interrupt altogether the flow of current across its moving contacts, it will be seen that it is perfectly correct to substitute for the notion of a variable resistance, the idea of a variable conductivity.

This interpretation of the phenomena of microphones suggests the possibility of solving in a practical manner the problem of the telephone transmitter, without having recourse to the use of carbon. Moreover there lies at the back of this a theory of the microphone more general than that based on the properties of carbon.

It suffices in fact to put in a state of vibration by the action of sound waves two or more movable contacts connected in a circuit, in order to produce the microphone effect independently of the use of carbon, that is to say as a direct and immediate consequence of any conductivity which is rendered variable.

For example Branly has proposed a microphone formed by crossing three steel points interconnected in a circuit.

Majorama has constructed a liquid micro-

phone and Professor Vanni has improved this up to a point of rendering it practical.

Preece has succeeded in using as a microphone an incandescent plate of platinum, cooling it simply by the action of the voice upon it. Mercury and metallic filings have also been employed for providing a variable conductivity in several researches on microphones.

In spite of the results attained, the only microphones in practical use are those of carbon. Practical experience always proves the superiority of this apparatus although theoretically any mass of variable conductivity might form a perfect transmitter.

There is therefore reason to conclude that the theory of the variable resistance or rather conductivity is not complete.

Bearing in mind that Hugues has been able to hear with a carbon microphone, using it as a receiver, one may affirm that the microphone phenomena are much more complex than they appear to be at first sight, just as are all the phenomena of telephony.

Many experiments have suggested to Mr. Alexandre Vaugean the idea that the electric current affects in a special manner the media constituting the imperfect conductors (the variable resistances) and that the presumed action of the currents on the said media is favorably affected by the extreme mobility of their points of contact. Hence he has been led to construct a special microphone forming the subject of the present invention, and using carbon in a manner which is novel from two points of view as follows:—

1. The carbon elements are inclosed in a glass receptacle which has been evacuated in order to prevent heat losses due to conductivity.

2. The receptacle is suspended in such a manner that it may vibrate intensely under the action of the shocks of the sound waves.

The suppositions have been abundantly confirmed in practice.

The passage of the current across the resistance of the carbon effects a physical modification of this element consisting in an extremely attenuated and extremely slight pulverization of its superficial layers.

The particles detached by the action of the current on the carbon masses and projected outwardly create a special medium endowed with actual conductivity.

As the position of the carbon elements in space is modified by the action of the sound, the topography of the zones of pulverized matter is modified at the same time thus 5 modifying also the action of the element as a conductor.

To sum up then, the variable resistance of imperfect contacts must be due simply to the modification in the topography or localization 10 of the zones formed by the matter detached from the carbon and projected outwardly. In other words it is not the conductivity of the carbon properly so called which is modified, but that of a medium derived 15 from the carbon, which medium is extremely mobile, extremely variable, and imparts to the phenomena of the microphone their primordial character—an incessant variability of resistance.

20 The absence of air (having as a result the avoidance of mechanical resistance) favors on the one hand the formation of a zone of special conductivity and the extreme sensitiveness of the system of suspension 25 of the new microphone, and facilitates on the other hand the transmigration of the zones of detached matter, which represent in fact the zones of variable resistance.

The realization of these two conditions 30 assures superiority in results attained according to the present invention, and at the same time makes it possible to establish a more complete theory of the microphone.

The microphone may be regarded in fact 35 as the seat of a miniature replica (because the phenomenon is much less intense), of what takes place in an arc lamp wherein there is a stream of particles detached by the action of the current and carrying the 40 current from the one carbon pole to the other. The multiplication of the points of contact and the weakness of the currents employed in telephony prevent any appreciable degradation or wasting away of the 45 positive poles or the transportation of pulverized matter to the negative poles. The slight amounts of matter detached from the masses create so to speak bridges of greater or less conductivity between the elements 50 which have come into imperfect contact one with another.

This new interpretation may be summed up briefly as follows:

The phenomena of the microphone result 55 from the passage of an electric current across ephemeral conductors, whose value is extremely variable, and which are created by the said currents due to the partial dissociation of certain conducting masses such as 60 carbon, metallic filings and so forth.

This theory explains in a manner which is quite satisfactory, the microphone of Preece using the incandescent plate, in view of the fact that the science of physics has proved 65 long ago the presence of material particles

in the flame or in the immediate neighborhood of incandescent bodies.

On the other hand if one may hear sounds by means of a microphone, as stated by Hugues, Siemens, and so forth, it is in view 70 of the bombardment of the particles detached from the carbon against the diaphragm.

In the accompanying drawings:—

Figure 1 shows a microphone formed of a 75 capsule or cell of glass suspended by three coil springs.

Fig. 2 shows a section on the line A—B of Fig. 1.

Fig. 3 shows a microphone composed of 80 three glass capsules connected one to another and to the periphery of the casing or sound reflector by an arrangement of elastic members.

Fig. 4 is a section on the line C—D of 85 Fig. 3.

Fig. 5 shows a transmitter composed of four microphone capsules of different construction supported by an elastic suspension.

Fig. 6 shows a section on the line E—F 90 of Fig. 5.

Fig. 7 shows a microphone composed of six capsules.

Fig. 8 is a section on the line G—H of 95 Fig. 7.

In Figs. 1, 2, 3 and 4, 1 is a capsule of glass into which have been sealed the pieces of metal or of carbon 2 and 3 which form the poles of the microphone. 4 is a small lug or hook formed in the mass of the glass 100 and coinciding with the little tube by which the capsule has been evacuated and sealed off. Inside capsule 1 are placed the small spheres 5 of carbon in light or loose contact. Very elastic springs 6 (Figs. 1 and 2) and 6 105 and 7 (Figs. 3 and 4) serve to suspend the capsule or capsules 1 from the points or parts 2, 3 and 4. 8 is a metallic reflecting surface. The construction of Figs. 3 and 4 only differs from that of Fig. 1 in that three 110 capsules are used.

In the form of construction shown in Figs. 5 and 6, 7 and 8, the microphone has four and six capsules respectively, these capsules being differently constructed from those described above. As is seen in Figs. 5 and 6 the capsule 9 containing the carbon is in this case made up of two face members 9^a and 9^b (Fig. 6). The ribs or projections 10, 11 and 12 formed on each face of a central member separate the cells 13, 14 and 15 in which the little spheres of carbon are placed. The carbon plates 16 and 17 are isolated from the capsules by means of ebonite annuli 18 and peripheral rings 19. The covers 20 and 21 hold these elements of the apparatus, locking the plates in position, being held together by the screws 22.

The central springs 23 connect together the capsules, (Figs. 5 and 6) or connect the 130

surrounding capsules to the central one (Figs. 7 and 8), while the outer springs 24 connect the capsules to the periphery of the reflector.

5 In view of their respective positions, and of the fact that they are under a sufficient tension, the springs assure the elastic suspension of the microphone capsules. At the least displacement of the layers of air by 10 means of the emission of sound, the system begins to vibrate under the action on the one hand of the waves of sound which strike against the front faces of the capsules, and on the other hand of the waves of sound reflected from the rear by the reflecting surface, and directed against the rear faces of the same capsules.

15 The various capsules are connected in parallel, one of their poles (the positive pole) 20 being formed by the carbon plate insulated from the cover, while the second pole (the negative) is formed by the covers themselves. The negative poles of the various capsules are easily connected by connecting 25 the springs by means of which the covers are supported.

It will be understood readily that any 30 number of capsules may be combined in one instrument according to requirements and that the capsules may have the carbon spheres at one face only or at both faces as in Fig. 6, in which case they are placed in front of a reflector such as 8.

Having thus described our invention what we claim as new and desire to secure by Letters Patent is:—

1. A microphone cell comprising two face plates and means for securing them together, a central member with partition ribs thereon, plates of carbon and means for supporting them with insulation within the face plates, and a plurality of spheres of carbon in the compartments of the cell formed by the ribs, the said spheres of carbon being in light contact with the carbon plates and with the central ribbed member of the cell.

2. A microphone for use in telephony comprising in combination an evacuated capsule, positive and negative terminals 50 fixed therein, a plurality of small pieces of carbon within the capsule and in light contact with one another, and with the terminals and resilient means by which said capsule is supported, said means permitting 55 said capsule to move with an equal degree of freedom in all directions.

In testimony whereof we affix our signatures in presence of two witnesses.

ALEXANDRE VAUGEAN.
ANTHONY DE LAVANDEYRA.
WILLIAM GARTHWAITE.
